UNITED STATES PATENT OFFICE.

FERDINAND L. STEGER, OF STEGER, ILLINOIS, ASSIGNOR TO STEGER & SONS PIANO MANUFACTURING COMPANY, OF STEGER, ILLINOIS, A CORPORATION OF ILLINOIS.

DESIGN FOR A PHONOGRAPH-CABINET.

54,184.

Specification for Design.

Patented Nov. 11, 1919.

Application filed August 13, 1917. Serial No. 186,058. Term of patent 7 years.

To all whom it may concern:

Be it known that I, FERDINAND L. STEGER, a citizen of the United States, residing at Steger, in the county of Cook and State of Illinois, have invented a new, original, and ornamental Design for a Phonograph-Cabinet, of which the following is a specification, reference being had to the accompanying drawings, forming a part thereof.

The drawing is a perspective view of a phonograph cabinet embodying this design.

I claim:—

The ornamental design for a phonograph cabinet substantially as shown.

In testimony whereof, I have hereunto set my hand at Steger, Illinois, this 6th day of August, 1917.

FERDINAND L. STEGER.
